INVENTOR.
Maurice D. Nolet,
By his Attorney,
J. H. McClosky.

UNITED STATES PATENT OFFICE.

MAURICE D. NOLET, OF MANCHESTER, NEW HAMPSHIRE, ASSIGNOR, BY MESNE ASSIGNMENTS, TO KITSON MACHINE SHOP, A CORPORATION OF MASSACHUSETTS.

COUNTING MECHANISM.

Application filed September 30, 1921. Serial No. 504,351.

This invention relates to counting mechanisms, and is especially concerned with the automatic counting of the laps produced by a lap winding machine.

As is well understood by those familiar with cotton mill machinery, a lap winding machine takes several sheets of carded cotton each wound in a roll, unwinds them, with the sheets superposed, draws out the fibres of the superposed sheets, and produces another sheet having a thickness predetermined by the setting of the machine and which is more uniform in structure than the original sheets. The sheet of cotton so produced is wound automatically on a spindle or rod, and the completed roll is known as a "lap". The present commercial lap winding machines include mechanism that automatically stops the machine when a predetermined number of yards of material have been wound on the spindle, thus completing a lap. The machine attendant then removes the lap, withdraws the spindle from it, replaces the spindle in the machine, and starts the machine into operation again.

It is desirable for many purposes, as for instance where the machine attendants are paid on a piece-work basis, to keep a record of the output of each machine. Accordingly, it is an important object of the present invention to devise a mechanism which will automatically count the laps produced by a lap winding machine. The invention also aims to devise a mechanism of this character which will be simple in construction, reliable in operation, and economical to manufacture. It is also an object of the invention to combine a counting mechanism with the automatic stop mechanism of a lap winding machine.

The nature of the invention will be readily understood from the following description when read in connection with the accompanying drawings, and the novel features will be particularly pointed out in the appended claim.

In the drawings,

Figure 1 is a side elevation of a portion of the well known Saco-Lowell lap winding machine equipped with a mechanism embodying the present invention; and

Fig. 2 is a front elevation of the parts shown in Fig. 1.

As above stated, the drawings show the invention applied to the Saco-Lowell lap

winding machine, and only so much of this machine has been shown as is necessary to an understanding of this invention.

In the drawings, 2 designates the main calendar roll shaft, and 3 a worm fixed to this shaft and meshing with a worm wheel 4 fast on a horizontal shaft 5 that extends at right angles to the shaft 2. At its opposite end this shaft has a pinion 6 fixed thereto and meshing with a gear 7 which is mounted to rotate on a stub shaft 8 projecting from a frame member 9. This gear 7 meshes with another gear 10 which rotates loosely about the stub shaft 11.

Power is transmitted to the machine through a clutch which is controlled by a lever 12 commonly known as the "drop bar." The left-hand end, Fig. 1, of this lever is mounted to move in a slot 13 formed in a bracket 14 secured to the machine frame, and it is normally held in its upper or operative position, as shown in the drawings, by a weighted latch 15 which is pivoted on the frame at 16. This latch is automatically thrown out at the completion of each lap, and when so moved it allows the bar 12 to drop, thus operating the clutch and stopping the machine. This automatic movement of the latch 15 is produced by the connections between the shaft 2 and the gear 10 just described, the gear for this purpose carrying a pin 17 which engages a dog 18 mounted loosely on the stub shaft 11. The gear 10 rotates in the direction indicated by arrow, Fig. 2. The dog is moved by the pin 17 and at the completion of each rotation of the gear 10 it swings the latch 15 far enough toward the right, Fig. 2, to disengage the notch or shoulder 19 in the latch from the lever 12. This allows the lever 12 to drop and throw out the clutch thus stopping the machine.

The construction above described, so far as general organization is concerned, is not substantially different from that heretofore used, and the present invention, utilizes the stop mechanism just described to perform the counting operation. The gears 7 and 10, however, for the purposes of this invention, do not have the same number of teeth, but one gear preferably has one more tooth than the other. Preferably the gear 10 has forty-nine (49) teeth and the gear 7 has fifty (50) teeth, although any other suitable ratio could be used. The gear 10, as stated

above, makes one rotation for each lap. Consequently, the gear 7 will stop, at the completion of each lap, one tooth behind its position when the previous lap was completed. The face of this gear is suitably graduated to form a dial, and a pointer 22, which may consist simply of a projection from the frame 9, cooperates with this dial to give an indication of the number of laps made. By noting the position of the gear 7 at the end of each day, a record of the number of laps made on the machine can readily be kept.

A particular advantage of this counting mechanism, as will readily be appreciated, is its simplicity. All the moving parts are necessary to operate the stop devices and the counting mechanism simply requires the making of a dial on the face of the gear 7 and the addition of a pointer to cooperate with this dial. It will also be appreciated that the embodiment of the invention above described is susceptible of modification without departing from the spirit or scope of this

invention. For instance, the dial and pointer can be reversed, the dial being stationary and the pointer rotating with the gear, although this construction obviously is the equivalent of that shown.

Having thus described my invention, what I desire to claim as new is:

In a lap winding machine having an automatic stop mechanism including a drop bar, a latch for releasably holding said bar and a gear operating at each revolution to actuate means to trip said latch, a lap counter comprising a second gear meshing with the first gear, one of said gears having one more tooth than the other, a dial on the face of the second gear, and a stationary pointer cooperating with said dial, whereby the difference in rotation of the two gears will cause said dial and pointer to indicate the number of actuations of said stop mechanism and thereby to indicate the number of laps produced by the machine.

MAURICE D. NOLET.
